UNITED STATES PATENT OFFICE.

ALVIN BAIR, OF TIFFIN, OHIO.

STARTER FOR AUTO-MOTORS.

1,141,033.

Specification of Letters Patent. Patented May 25, 1915.

Application filed October 9, 1913. Serial No. 794,812.

To all whom it may concern:

Be it known that I, ALVIN BAIR, a citizen of the United States, residing at Tiffin, in the county of Seneca and State of Ohio, have 5 invented a new and useful Starter for Auto-Motors, of which the following is a specification.

The device forming the subject matter of this application is a starter, adapted to be 10 assembled with the shaft of an engine of a motor propelled vehicle, to permit the shaft to be initially rotated, without compelling the operator of the vehicle to descend therefrom.

One object of the present invention is to 15 provide a starter of the type indicated which will work no change in the standard construction of the crank and the engine shaft.

Another object of the invention is to provide 20 a starter which may be operated with safety to the user.

The invention aims to provide means whereby the clutch elements of the crank and the engine shaft may be operatively 25 connected.

It is within the scope of the invention to improve generally and to enhance the utility of devices of that type to which the present invention appertains.

With the above and other objects in view which will appear as the description proceeds, the invention resides in the combination and arrangement of parts and in the 30 details of construction hereinafter described and claimed, it being understood that changes in the precise embodiment of the invention herein disclosed can be made within the scope of what is claimed without departing from the spirit of the invention.

In the accompanying drawings:—Figure 1 shows in top plan, a portion of a motor propelled vehicle to which the device forming the subject matter of this application has been applied. Fig. 2 is an end elevation 40 of the vehicle showing the parts of the starter as the same will appear when the invention has been operated to effect an initial rotation of the crank shaft; Fig. 3 is a side elevation of the structure shown in Fig. 1, parts being broken away; Fig. 4 is an end elevation similar to Fig. 2, but showing the 45 starter in its normal position; Fig. 5 is a perspective of the clutch actuating lever.

In the accompanying drawings, the frame 50 or body of a vehicle is shown and denoted generally by the numeral 1, the numeral 2

indicating the engine, the shaft whereof is denoted by the numeral 3, the same carrying a clutch 4. A crank shown at 5 is provided with a clutch 6 adapted to coöperate with the clutch 4, the clutches 4 and 6 being normally held out of engagement by means of a spring 7. The crank 5 is shown as journaled for rotation in bearings 8 and 9.

The foregoing constitutes a portion of a 65 common and well known construction meriting no more extended description than that above given.

In carrying out the invention, a curved frame is secured to the crank 5, the said 70 frame including a peripherally grooved segment 10. This segment 10 may be of any desired shape, contour and length. At one end the segment 10 carries a clip 11 whereby the segment is detachably assembled with 75 the crank 5. Secured to the segment 10 adjacent the other end thereof is a spoke 12, carrying a clip 14 which is detachably connected with the crank 5. The curved frame hereinbefore mentioned may include other 80 spokes, one of which, indicated by the numeral 15, extends between the segment 10 and the spoke 12.

The foregoing details may be varied within large limits, without jeopardizing the 85 utility of the invention, it being necessary, merely, that a curved frame of some appropriate sort is detachably connected with the crank 5.

A flexible element, such as a chain 16 is 90 secured at one end to the clip 11 and, under normal conditions, as shown in Fig. 4, the flexible element 16 lies in the grooved periphery of the segment 10. The flexible element 16 is trained about a sheave 17 which is 95 journaled for rotation upon a bracket 18 carried by any accessible portion of the frame of the vehicle. Beyond the sheave 17, the flexible element 16 is passed through a guide 19 which may be in the form of a tube 100 or pipe. In the present instance, the forward end of the guide tube 19 is mounted on an arm 20, constituting a part of the bracket 18 on which the sheave 17 is journaled, the rear end of the guide tube being extended 105 through the dash board 21. Secured to the rear end of the flexible element 16 and within easy reach of the occupant of the vehicle is a handle 22.

Pivoted to the clip 14 is a link 23 attached 110 to a flexible element 24, in the present instance shown in the form of a chain. The

intermediate portion of the flexible element 24 is detachably connected as indicated at 25 with one end of a retractile spring 26, the other end of which is connected with a 5 bracket 27 mounted upon the frame of a vehicle. That end of the flexible element 24 which is adjacent the bracket 27 hangs slack as indicated at 28 and is connected with the bracket 27 or is otherwise fixed.

10 Extending transversely of the frame of the vehicle is a lever 29, shown in detail in Fig. 5. At its inner end, the lever 29 terminates in a fork 30, engaged with the crank 5 in front of the clutch 6. The outer end of 15 the lever 29 is fulcrumed as indicated at 31 upon a support 32, secured to some convenient portion of the vehicle frame. If desired, the lever 29 may be given a quarter twist as indicated at 33, so that the fork 30 20 will stand vertically, to the end that the fork may coöperate properly with the clutch 6. A connection, which may be a chain, indicated at 34, is pivoted as shown at 34^a to the intermediate portion of the lever 29, the 25 rear end of the connection 34 being pivoted to a pedal 35 fulcrumed as indicated at 36 upon the footboard 36^a, or otherwise located within easy reach of the foot of the operator.

The practical operation of the structure 30 hereinbefore set forth is as follows:—Presupposing that the parts are positioned as shown in Figs. 3 and 4, the free end of the pedal 35 is pressed down, whereupon the connection 34 will tilt the lever 29 upon its fulcrum 31, 35 the fork 30 of the lever 29 engaging in front of the clutch 6 and moving the clutch 6 rearwardly, so that the same coöperates properly with the clutch 4 on the engine shaft 3, the spring 7 being put under tension. Thus, 40 the crank 5 is coupled up operatively with the engine shaft 3. Presupposing that the parts are positioned as shown in Fig. 4, the handle 22, along with the chain 16, is drawn rearwardly, the chain 16 riding around the 45 sheave 17. By this operation, the curved frame comprising the segment 10 and its connecting parts will be swung to the right until the frame moves from the position shown in Fig. 4 to the position shown in 50 Fig. 2. By this operation, a partial rotation will be imparted to the engine shaft 3, since the curved frame is connected with the crank 5 by means of the clips 14 and 11.

By the operation above described, the link 55 23 will be carried around from the position shown in Fig. 4 to that shown in Fig. 2, the link standing vertically, or nearly so, depending upon the position of the crank 5, the link bearing against the side of the 60 crank; all of which will be obvious from Fig. 2. By the operation last above de-

scribed, the chain 24 will be drawn upon, and the spring 26 will be put under tension. When the handle 22 is released, the spring 26 will react to restore the parts to the positions shown in Fig. 4. The function of the looped portion 28 of the chain 24 is to prevent undue elongation of the spring 26 and to prevent the curved frame comprising the segment 10 and adjacent parts from moving 70 too far.

The throw of the curved frame 10—12 together with the amount that the spring 26 is elongated, may be varied by shifting the point of connection with respect to the outer end of the spring 26, it being obvious that any link in the chain 24 may be hooked in the end of the spring 26. In case the motor should be working improperly, the chains 16 and 24 may be detached, respectively, from the segment 10, and the link 23, whereupon the engine may be cranked up in the usual manner.

One of the advantages of the present structure is that owing to its manifest simplicity, no changes are necessary in the standard forms of crank mechanism as at present on the market.

Having thus described the invention, what is claimed is:—

1. In a device of the class described, co-operating elements comprising a crank and a curved frame secured thereto; a flexible element trained about the curved frame; a rigid link located in a common plane with the crank; a spring; means for anchoring the spring; means for connecting the spring with the link; and a pivot element uniting the link with one of said coöperating elements at a point between the center of rotation of the crank and the outer end thereof, the length of the link being greater than the distance from the pivot element to the center of rotation of the crank.

2. In a device of the class described, a 105 crank; a curved frame secured thereto; a flexible element trained about the curved frame; a flexible element connected with the curved frame and including a bight; a spring bridging the bight and adapted at one end for connection with the flexible element at spaced points, thereby to vary the size of the bight; and means for fastening the other end of the spring and the flexible element.

In testimony that I claim the foregoing as my own, I have hereto affixed my signature in the presence of two witnesses.

ALVIN BAIR.
